UNITED STATES PATENT OFFICE.

GEORGE H. TAYLOR, OF RICHMOND, VIRGINIA.

ATTACHED BAND-FASTENER.

1,241,301.

Specification of Letters Patent. Patented Sept. 25, 1917.

Application filed March 2, 1917. Serial No. 152,058.

To all whom it may concern:

Be it known that I, GEORGE H. TAYLOR, a citizen of the United States, residing at Richmond, in the county of Henrico and 5 State of Virginia, have invented certain new and useful Improvements in Attached Band-Fasteners, of which the following is a specification.

This invention relates to an attached band 10 fastener and particularly to a construction wherein the fastener plate is formed separate from the band and attached thereto when the fastener is to be applied in use.

The invention has for an object to provide a new and improved construction of band provided with means to engage a fastener plate and prevent either lateral or longitudinal movement thereof relative to the band when attached thereto.

20 A further object of the invention is to provide means upon such a band to prevent movement of either the band or fastener on the material to which it is applied when the free end of the band is drawn taut preliminarily to securing it by the lugs of the 25 fastener.

Another object of the invention is to form a particular construction of fastener plate adapted for application to a band having a retaining lug or projection to engage 30 the plate.

Other and further objects and advantages of the invention will be hereinafter set forth and the novel features thereof defined by the 35 appended claims.

In the drawing—

Figure 1 is a perspective of the plate partially attached to the band;

Fig. 2 is a similar view of the completed 40 attachment;

Fig. 3 is a perspective showing the free end of the band clamped to the fastener;

Fig. 4 is a section on line 4—4 of Fig. 2;

Fig. 5 is a detail of the band end for at- 45 tachment;

Fig. 6 is a side elevation of a modified form;

Fig. 7 is a perspective of a modified form of fastener;

50 Fig. 8 is a side elevation of this form attached to a band; and Fig. 9 is a perspective of a further modified form of fastener plate attached.

Like numerals refer to like parts in the 55 several figures of the drawing.

In Figs. 1, 2, 3 and 4 the novel construction of band is shown as attached to the

construction of fastener plate disclosed in my Patent 1,218,337, Mar. 6, 1917, but it is adapted for application to any form of such 60 plate as will be hereinafter set forth. In these figures the band 10 is provided with a lip or retaining lug 11, preferably formed from the body thereof, and bent at an angle thereto to engage and embrace an edge 12 65 of the fastener plate 13. This plate is formed with clamping lugs 14 and 15 adapted to be bent or folded toward the plate to secure the drawn end 16 of the band, as shown in said application and also 70 in Fig. 3 herein. The plate is also provided with holding prongs or projections 17 to engage the material to which the fastener is applied and prevent slipping thereof during the drawing and clamping action. The end 75 18 of the band beyond the lip 11 extends over the face of the plate and is bent beneath the end or edge thereof opposite to the edge engaged by said lip. This effectively retains the plate against either lateral 80 or longitudinal movement upon the band.

The lip or lug 11 is shown as cut from the body of the band but may be formed in any desired manner to form an interlocking means between an edge of the plate and the 85 band.

In Fig. 6 a modified form of the invention is illustrated in which the prongs 17, shown in Fig. 1, are omitted and a band 20 attached to a fastener plate 21 as before described. The band however is formed with a bur or roughened portion 22 upon its under side to engage the material to which the fastener is applied and prevent slipping thereon during such application. 95

Fig. 7 shows a novel form of fastener plate 23 provided with a slot 24 in the body thereof with an edge of which the lip 25 on the band 26 engages. The end 26 of the band beyond this lip is bent under the plate 100 as described in connection with Fig. 1. In this form of the invention the end 26 of the band beneath the plate is formed with a bur or roughened portion 27 to prevent slipping of the fastener when applied. See 105 Fig. 8.

Fig. 9 illustrates a further modification of the fastener plate, similar in general construction to that shown in Figs. 7 and 8, but in which the plate 28 is provided at one 110 edge with a holding lug 29 to embrace the end of a band 30. This band is also provided with a lip 31 to engage a wall of a slot 32 in the plate 28. In this form of the

- invention the lip is formed adjacent the end of the band and the latter is not bent under the plate. In each form the lip is directed toward the free end of the band 5 so as to prevent longitudinal movement of the plate toward the body of the band while the means for holding the end of the band beyond the lip prevents such movement in an opposite direction.
- 10 In the practical manufacture and shipping of these fasteners it is desirable to transport the fastener plates having the angularly bent clamping lugs separately from the bands as the latter can then be packed in 15 very close manner and the plates attached to the proper length of band when the latter is to be applied to a pipe covering or otherwise. The lip or lug not only connects the plate and band but forms a gage to determine the length of band end beyond the 20 lip so that the proper amount thereof may be bent over the plate or otherwise held. This is particularly desirable when the bands have been cut to length for certain 25 size of pipe as if there were too much overlap the balance of the band would not be sufficiently long to extend around the pipe and properly fasten. The shipping and storing of the fastener plates separately 30 from the bands prevents injury to the lugs of the former and occupy much less space in stock or transportation. The construction of the band permits the very easy and convenient application of the plate thereto 35 without the use of tools. When thus secured the fastener may be easily handled in applying the same without the danger or annoyance of the plate becoming disconnected from the band during such operation.
- 40 What I claim is:—
1. In a band fastener, a bendable band, a fastener plate disposed at one end thereof, interlocking means connecting one edge of the plate with said band to prevent longitudinal movement in one direction, and means connecting the plate and band to prevent similar movement in an opposite direction.
  2. In a band fastener, a bendable band, 50 a fastener plate disposed at one end thereof, interlocking means connecting a portion of said plate with the band disposed to provide a predetermined length of band beyond said means, and a connection between the free 55 end of said band beyond said means and said plate.
  3. In a band fastener, a bendable band, a fastener plate to be applied at one end thereof, projecting means upon one of said 60 members to engage an edge wall of the other, and means to connect the end of said band beyond said lug to said plate.

4. In a band fastener, a band provided with a retaining lip, a fastener plate adapted to have one edge embraced by said lip, 65 and means connecting the free end of said band adjacent said lip to said plate.

5. In a band fastener, a separate fastener plate over one face and edge of which one end of a band is adapted to be folded, means 70 carried by the band adjacent its folded end to embrace the opposite edge of said plate, and means carried by the plate to secure the opposite end of the band.

6. In a band fastener, a separate fastener 75 plate, a band to which said plate is applied, a projection extending from the band to embrace an edge of the plate, means connecting the end of the band beyond said projection with said plate, and a roughened portion 80 upon said band to prevent slipping of the fastener.

7. In a band fastener, a band of bendable material formed adjacent one end thereof with a retaining lug projected toward the 85 free end of the band, and fastening means adapted to be engaged at opposite edges by said lug and the free end of the band.

8. In a band fastener, a fastener plate, a band formed of bendable material and having adjacent one end thereof a retaining lug cut from its body and bent outward therefrom toward said end of the band to engage said plate, and means connecting said end to said plate independent of said 95 lug.

9. In a band fastener, a fastener plate, a band formed of bendable material to embrace a portion of said plate and having adjacent one end thereof a retaining lug cut 100 from its body and bent outward toward said end of the band, and a bur formed from said band to provide a roughened holding portion.

10. In a band fastener, a bendable band provided with a projecting retaining means, a fastener plate adapted to be attached thereto by said means and provided with parallel clamping lugs and a slot within the 105 body thereof.

11. In a band fastener, a bendable band provided with a projecting retaining means, a fastener plate adapted to be attached thereto by said means and provided with parallel clamping lugs and a slot within the 115 body thereof, and a holding lug at one edge of said plate adapted to embrace the end of said band beyond said means.

In testimony whereof I affix my signature in the presence of two witnesses.
